Patented Oct. 5, 1909.

UNITED STATES PATENT OFFICE.

CHARLES PARRIS STEWART, OF LOS ANGELES, CALIFORNIA, ASSIGNOR TO NATIONAL SUGAR COMPANY, OF LOS ANGELES, CALIFORNIA. A CORPORATION OF ARIZONA TERRITORY.

PROCESS FOR MAKING SUGAR.

935,942.

Specification of Letters Patent.

Patented Oct. 5, 1909.

Application filed March 6, 1908. Serial No. 419,469.

To all whom it may concern:

Be it known that I, CHARLES PARRIS STEWART, a citizen of the United States, residing at Los Angeles, in the county of Los Angeles and State of California, have invented a new and useful Process for Making Sugar, of which the following is a specification.

This invention relates to the synthetic process for the manufacture of sugar, and it is an object thereof to provide a process whereby sugar can be manufactured from ordinary and inexpensive substances.

This application is filed as a continuation of my application entitled process of making sugar, S. N. 368,267, filed April 15, 1907.

In the accompanying drawings I have illustrated a form of apparatus which may be employed in operating my process, the figure illustrated being a diagrammatic view of the apparatus employed, parts being broken away and enlarged for clarity of illustration.

In the form of apparatus shown in the drawings I designate a steam boiler of any usual type connected by a pipe 2 to a super-heating furnace 3. Furnace 3 is provided with a pipe 4, or a series of the same, of heat resisting material, preferably clay, and the steam from the boiler passes through this pipe, the amount being controlled by valve 5 on pipe 2. From the outlet end of clay pipe 4, pipe 6 leads to a carbon retort 7. This carbon retort is composed of an inner heating chamber 8, containing charcoal 9, or other form of carbon, which is heated by means of burners 10. After passing through the heated carbon the gases pass out through pipe 11 to a cooling tank, or condenser, 12, and thence through a pipe 13 to a compressor 14. After being compressed the gases pass into a storage chamber 15 provided with a pressure gage 16 so that a steady pressure may be maintained upon the gases by the compressor. Passing from chamber 15 through pipe 17, the gases pass into precipitator 18. This precipitator comprises a pipe 19, preferably brass or other non-magnetic material, a set of preferably alternating electro-magnets 20 surrounding the pipe to set up a magnetic field within it. Directly beyond magnets 20 is located a pair of electrical discharge plates 21 connected to an induction coil, or other high tension machine (not shown), for the purpose of main-

taining an electric discharge across the gap between the plates. Beyond the discharge plates pipe 19 narrows down, as at 22, and is controlled at this point by a valve 23. Directly beyond valve 23 and on the constricted part of the pipe is a second set of electro magnets 24, also preferably alternating. Pipe 19 widens out beyond electro-magnets 24 and is provided with a second pair of discharge plates 25 preferably connected to the same source of electrical energy supply as plates 21. Downwardly inclined spout 26 on the enlarged end of the pipe completes the apparatus.

The operation of my process is as follows:—Steam is generated in boiler 1 and admitted to furnace 3 in the proper volume as determined by the capacity of the apparatus and as the experience of the operator dictates. The temperature of furnace 3 is normally about 2000° F., and the steam is highly superheated in passing through clay pipes 4. This superheated steam passes immediately through the heated charcoal or carbon 9 in retort 7, and the oxygen of the steam combines with the carbon and leaves the hydrogen free, as far as can be ascertained, as follows:—

This reaction may be affected by the leakage of foreign gases from the atmosphere into the apparatus, but, unless the leakage is of large proportions, the reaction is substantially as above represented. The temperature of the charcoal is approximately that of its incandescent heat, and, on account of this high temperature and the excessive presence of the carbon, CO is formed rather than CO₂. The mixture of gases, CO and H₂, passes off through pipe 11 to condenser 12 where it is cooled to pass into the compressor. The compressor operates to place the mixture of gases under a pressure of from 30 to 60 pounds per square inch and they are stored in chamber 15 under that pressure. The mixture of gases then passes through the precipitator and is subjected alternately to the influence of magnetic fields and electrical discharges. The first magnetic field is formed by magnets 20 and the mixture of gases passes through this field and then through the electrical discharge between plates 21, which, in the present plant, dis-

ross a three inch gap. The rest of the pipe is then encountered by valve 23 and next through the ignets 24. The mixture then exits atmospheric pressure and passes a second electrical discharge before 25. The alternate action of magnetic and electrical influences combination of the gases to form pure sugar of the formula

Construction of the precipitator is of importance, the only requirement being the passage of the gases through magnetic influences. The arrangement, however, has been found to be best. When this product emerges from the precipitator it is comparatively safe as there is no danger of decomposition

in conditions enumerated above, the intervention of any foreign gas as atmospheric, the reaction's place in the precipitator is, as can be ascertained, as follows:—

If a small portion of atmospheric entrance to the apparatus prior to passage through the carbon retort, is been found to be the case in operations of this process, such the following will take place:—

amount of mixtures of the atmosphere would cause a larger proportion in the left hand member of the equation and therefore give a larger amount of CO_2 in the results. This gas, in turn, does not influence the action of the process, as does neither the nitrogen nor the oxygen of the atmosphere which is therefore ignored in the equations.

Operation of this process about by weight of charcoal and water. The resulting weight of chemically pure sugar is some 75%, or more, of the weight of the charcoal and

foregoing description it will be seen that the process consists essentially in the combination of carbon monoxide and hydrogen. The method for obtaining these gases may be other than that described in the specification, but it is evident that they may be supplied in the required proportions and be equally effective. They are conveniently obtained from water and the required proportions are thereby ap-

plied to the apparatus, what I

claim as new and desire to secure by Letters Patent is:—

1. The process of forming sugar synthetically which comprises treating combined hydrogen and oxygen with carbon in substantially the proportions to produce the product desired. 70

2. The herein described synthetical process which comprises forming sugar in a continuous operation by combining carbon, 75 hydrogen and oxygen in substantially the proportions to produce the product desired.

3. The herein described synthetical process which comprises forming sugar in a continuous operation by treating combined 80 hydrogen and oxygen with carbon in substantially the proportions to produce the product desired.

4. The process of forming sugar synthetically which comprises combining carbon, 85 hydrogen and oxygen in substantially the proportions to produce sugar, and then passing the resultant gases through magnetic and electrical influences.

5. The process of forming sugar comprising combining carbon, hydrogen and oxygen in substantially the proportions to produce 90 $C_{12}H_{22}O_{11}$ and then subjecting the resultant gases to magnetic influence.

6. The process of forming sugar comprising combining carbon, hydrogen and oxygen in substantially the proportions to produce 95 $C_{12}H_{22}O_{11}$ and then passing the resultant gases through the field of an alternating magnet. 100

7. The process of forming sugar by the synthetic means of combining carbon with oxygen, adding free hydrogen to the combined carbon and oxygen, and then passing the resultant mixture through magnetic and 105 electrical influences.

8. The process of forming sugar synthetically comprising combining oxygen with carbon to form CO , adding free hydrogen, and then passing the resultant mixture 110 through magnetic and electrical influences.

9. The process of forming sugar comprising first superheating steam, then passing the superheated steam over heated carbon, and finally subjecting the resultant gases 115 to magnetic and electrical influences.

10. The process of forming sugar which comprises mixing substantially twelve parts of CO with twelve parts of H_2 , and then subjecting the mixture to magnetic and 120 electrical influences.

11. The process of forming sugar comprising passing superheated steam over heated carbon, to form carbon monoxide and hydrogen and then combining the resulting gases 125 in substantially the proportions to produce the product desired.

12. The manufacture of cane sugar synthetically by passing super-heated steam through carbon heated to a high tempera- 130

- ture, thereby decomposing the steam into gases, cooling the gases formed and compressing the same, and condensing the said gases by means of an electric current.
- 5 13. The manufacture of cane sugar consisting in passing superheated steam over highly heated carbon, thereby decomposing the steam into gases, cooling and compressing the gases formed and subjecting the same 10 to magnetic influence, and condensing the gases by a current of electricity.
14. The manufacture of cane sugar synthetically consisting in passing super-heated steam through highly heated charcoal, there- 15 by decomposing the steam into gases, cooling the gases formed and compressing the same, and condensing the said gases by means of an electric current.
15. The process of manufacturing cane 20 sugar synthetically by passing super-heated steam through carbon heated to a high temperature, cooling and compressing the gases generated from the super-heated steam and carbon, and condensing into cane sugar the 25 said gases by passing through the same a current of electricity.
16. The process of manufacturing sugar consisting first of super-heating steam, passing the super-heated steam through red-hot 30 carbon, cooling the gases formed and compressing the same, and condensing the said gases by means of an electric current.
17. The process of manufacturing sugar consisting first, of super-heating steam, 35 second, passing the super-heated steam through heated charcoal forming carbonic oxid and hydrogen, cooling said gases and compressing the same, and condensing the carbonic oxid and hydrogen by passing 40 through the same a current of electricity.
18. The process of manufacturing sugar synthetically by passing super-heated steam through carbon heated to a temperature of from eight hundred (800) to one thousand 45 (1000) degrees centigrade, cooling and compressing the gases formed, and condensing the said gases into cane sugar by passing a current of electricity through the same.
19. The synthesis of organic compounds, 50 comprising treating a substance containing hydrogen and oxygen with a heated carbonaceous substance, and subjecting the resulting gases to treatment by an electric current.
- 55 20. The synthesis of organic compounds, comprising effecting a chemical reaction between a substance containing hydrogen and oxygen, and a carbonaceous substance, cooling the resulting gases, and subjecting the 60 same to treatment by an electric current.
21. The synthesis of organic compounds, comprising effecting a chemical reaction between water and a heated carbonaceous substance, producing carbon monoxid and hydrogen, cooling the resulting gases, and passing an electric current through the same.
22. The synthesis of organic compounds, comprising effecting a chemical reaction between water and a heated carbonaceous substance, producing carbon monoxid and hydrogen, compressing the same, and passing an electric current through the mixed gases.
23. The synthesis of organic compounds, comprising effecting a chemical reaction between mixed carbon monoxid and hydrogen, by cooling, compressing, and passing an electric current through the mixed gases.
24. The synthesis of carbohydrates, comprising treating a substance containing hydrogen and oxygen with a heated carbonaceous substance, and subjecting the resulting gases to treatment by an electric current.
25. The synthesis of carbohydrates, comprising effecting a chemical reaction between a substance containing hydrogen and oxygen, and a carbonaceous substance, cooling the resulting gases, and subjecting the same to treatment by an electric current.
26. The synthesis of carbohydrates, comprising effecting a chemical reaction between water and a heated carbonaceous substance, producing carbon monoxid and hydrogen, cooling the resulting gases, and passing an electric current through the same.
27. The synthesis of carbohydrates, comprising effecting a chemical reaction between water and a heated carbonaceous substance, producing carbon monoxid and hydrogen, compressing the same, and passing an electric current through the mixed gases.
28. The synthesis of carbohydrates, comprising effecting a chemical reaction between mixed carbon monoxid and hydrogen, by cooling, compressing, and passing an electric current through the mixed gases.
29. An apparatus for producing sugar comprising a retort containing carbon, means to heat said carbon, means to supply super-heated steam to said carbon at the bottom thereof, means to cool the gases from said retort, and means to electrify and combine the same.
- In witness that I claim the foregoing I have hereunto subscribed my name this 27th day of February, 1908.
